(57) **CLAIM**

I claim the ornamental design for the hair brush, as shown
and described.

DESCRIPTION

FIG. 1 is a perspective view of the hair brush.

FIG. 2 is a right view of the hair brush (the left side view,
top view and bottom view being identical to the right side
view of the hair brush).

FIG. 3 is a front end view of the hair brush wherein FIG. 3
is enlarged to better show details of the hair brush; and,

FIG. 4 is a rear end view of the hair brush wherein FIG. 4
is enlarged to better show details of the hair brush.
